UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,809, dated May 16, 1899.

Application filed April 22, 1899. Serial No. 714,115. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a certain new and original Design for a Manhole-Cover, of which the following is a specification, reference being had to the accompanying drawings, forming part thereof, in which—

Figure 1 is a top or plan view of the manhole-cover of the design of my invention, and Fig. 2 is a transverse sectional view on the line $x-x$ of Fig. 1.

The leading feature of my design consists of the unitary structure made the subject of illustration and having the shape or configuration hereinafter described.

Referring to the drawings, A is the circular cover, having the convex-shaped bottom a , the inner surface of which is curved at a' to the

slanting and tapering inner wall a^2 , provided at the top with a broad projecting rim a^3 , with a circular flat-edge surface a^4 , and the exterior surface of the wall of the cover below the projecting rim a^3 is rounded at a^5 , where it merges with the convex bottom, which latter is provided with four downwardly-projecting ribs b , b' , b^2 , and b^3 , as clearly illustrated in Fig. 1 of the drawings.

Having thus described my invention, what I claim as new, and desire to secure by Letters Patent, is—

The design for a manhole-cover, substantially as illustrated and herein described.

In testimony whereof I have hereunto set my signature in the presence of two subscribing witnesses.

THOMAS P. GREGER.
